UNITED STATES PATENT OFFICE.

ATHANASIOS PAPANASTASIOU, OF EAST PITTSBURGH, PENNSYLVANIA.

DIVING APPARATUS.

1,223,515.

Specification of Letters Patent.

Patented Apr. 24, 1917.

Application filed July 15, 1916. Serial No. 109,587.

To all whom it may concern:

Be it known that I, ATHANASIOS PAPANASTASIOU, subject of the King of Greece, residing at East Pittsburgh, in the county 5 of Allegheny and State of Pennsylvania, have invented certain new and useful Improvements in Diving Apparatus, of which the following is a specification.

The present invention has relation to diving apparatus and as its primary object contemplates the provision of a novel and improved housing wherein a circulation of air may be maintained; thus enabling the divers or other occupants thereof to remove their 15 diving helmets with safety during the resting periods.

As a further object the invention aims to provide a novel arrangement whereby the air within the housing or shell may be kept 20 in a purified condition at all times thereby insuring safety to the occupants and novel means to selectively control the admission of such purified air into the several independent compartments.

25 A still further object of the invention resides in the provision of an ingress and egress compartment such as will permit the ingress or egress of the divers to the resting compartment in such manner as to preclude 30 the entrance of water into the latter compartment.

Another object is to provide novel means whereby the divers may reach the bottom of the sea from the shell or housing either when 35 the housing is resting upon the bottom or when conditions render it impractical to allow the same to assume such a position.

A yet further object is to provide for the proper distribution of air to the divers' helmets and to maintain a circulation of air throughout the interior of the diving suits such as will not only aid in the maintenance 40 of the divers in a healthy condition but moreover act as a warming medium when the sea 45 is extremely cold.

Although my invention is primarily designed to be used in connection with the gathering of sponges and the like it is to be understood that I am not limited in this 50 respect since the device may be used advantageously in subterranean operations of various different sources.

Various other objects and advantages will 55 become apparent during the continuance of the following description.

These objects are accomplished by such

means as are shown in their preferred form in the accompanying drawings, described in the following specification and then more specifically pointed out in the appended 60 claims.

In the accompanying drawings wherein like characters designate like parts throughout the several views:—

Figure 1 is a view in cross section illustrating the shell or housing of my invention as submerged, 65

Fig. 2 is a view in side elevation of a diving suit showing in conjunction therewith the means for introducing air into the 70 helmet and distributing air by means of another conduit about the body of the diver,

Fig. 3 is a view showing in detail the double door arrangement which I have adopted 75 as the preferred form of my invention.

In its present embodiment my invention consists of an outer shell 10 which forms the main housing and an inner shell 11 which is generally utilized as a purifying chamber, means such as indicated by the numeral 12 80 being positioned on the outer shell 10 whereby the entire structure may be raised or lowered and other means as indicated at 13 depending from the outer shell to form a supporting stand as shown in Fig. 1. It is 85 arbitrary as to the material used in the construction of the outer and inner shell. However the terrific pressure prevalent at the great depths under the surface of the sea render it advisable to use a stout metal for 90 this purpose.

Likewise it is advisable to construct the stand 13 of a strong and durable metal. In the present embodiment I have shown this stand of skeleton construction, the same 95 comprising a series of angle bars and knee braces yet it is to be borne in mind that this construction is not final and that it may be suitably modified during the reduction to practice. 100

A platform 14 extends about the lower portion of the outer shell 10 while a second platform 15 is spaced above the first platform, both being braced by such means as shown at 16. Railings 17 and 18 may be 105 positioned on the platform as shown in Fig. 1, such railings preventing the accidental falling of the divers from the platforms as is obvious. The lower platform is equipped with depending ladders 19 and 20 whereby 110 when the supporting stand 13 is resting on the bottom the divers may descend. How-

ever as above intimated inasmuch as conditions often render it impractical to allow the housing to rest upon the bottom I also provide means whereby the divers may descend under those conditions.

With the above end in view I equip the lower platform 14 with a pivoted ladder 21, as at 22 and, in turn, provide a second ladder 23 which has pivotal connections with the first ladder as at 24. I then provide one of the braces 16 with a bracket 25, the latter carrying a pulley 26 about which is trained a cable 27 whose one end is connected with the free end of the ladder 23. The other end of the cable 27 is wound about a windlass 28 whereby upon operation of the handle 29 the ladders may be raised or lowered to compensate for the varying depths of the housing.

Entrance may be had into the outer shell by way of the double doors 30 and 31; one door opening outwardly and the other door opening inwardly and likewise access may be had to the inner shell by way of the doors 32 and 33. A ladder 34 is positioned within the outer shell 10 adjacent the doors 30 and 31 which leads to an upper compartment A so that the divers may reach the compartment quickly and easily. A partition 35 and another partition 36 aid in the formation of other compartments B and C, entrance being had between compartments A and B by means of doors 37 and 38 while a trap door 39 controls communication between compartments B and C.

Compartment C which forms the ingress and egress chamber has an outlet through the doors 40 and 41 and a ladder 42 leads from the opening 43 in the partition 36 to a point in proximity to the doors 40 and 41 whereby the divers may readily pass therethrough. When the apparatus is submerged compartment C is filled with water as is the space between doors 40 and 41.

On one side of the shell 10 and preferably adjacent the compartment C I provide a bulk head 44 so as to neutralize the weight of the apparatus when the compartment C is filled with water. A tube 45 extends upwardly from the bulk head 44, carrying at its upper end a cover 46, and through this tube the main air supply hose 47 extends. Hose 47 is introduced into compartment B through the way 48 and it is there connected with an auxiliary pump 49. Communication between the tube 45 and compartment B may be had by way of doors 50 and 51 so that if occasion should require the divers may enter the tube 45 and mount the ladder 52.

Suitable ladders 53 and 54 lead from the partition 36 to the doors 38 and 50 so as to provide means whereby ready ingress and egress may be had to and from the compartment B.

An air hose 55 extends from the auxiliary

pump 49 to the diver's helmet 56 while a second air tube 57 extends from the auxiliary pump to a point below the level of the water within the shell 11. The purified air from the interior of shell 11 may be introduced to compartments A and B by way of valve 58 and tube 59 while such air may also be introduced to the tube 45 by means of valve 60 and conduit 61. It will be noted that air from the compartment B will be drawn into the pump and thereupon forced through the water in the shell 11 whereas the air entering the pump by way of supply tube 47 is pumped directly to the divers.

As illustrated in Fig. 2 tube 55 is equipped with a branch tube 62 which enters the diver's suit 63. That portion of the tube 62 which enters the diver's suit is perforated as shown at 64 thereby supplying the air about the body of the diver such as will form a protection against cold.

In use, the divers enter the shell A before the latter is submerged by way of the doors 30 and 31 from whence they may enter either of the compartments A and B. The divers suits may be put on in either of the compartments and the helmets attached. The divers then enter compartment C by way of trap door 39 and inasmuch as the doors 40 and 41 are closed the water from compartment C will not enter compartment B. After entering compartment C the divers close the trap door 39 and they may then find egress from the compartment by way of doors 40 and 41.

If the apparatus is to be used by a number of divers the dimensions of the shells are accordingly increased and it is to be understood that such changes may be made without departing from the spirit and scope of my invention.

Having thus fully described my invention what I claim as new and desire to secure by Letters Patent is:—

1. A diving apparatus comprising a housing including an outer and inner shell, said inner shell forming a water chamber, means to force air from said outer shell through the water in said inner shell and means to selectively dispense the air from said inner shell to said outer shell.

2. In an apparatus of the character described a housing including an outer and inner shell, said inner shell forming a water compartment, said outer shell being divided into a series of independent compartments, one of said last mentioned compartments being normally filled with water, and means to maintain a continual circulation of air through the other compartments and pass the air through the water in said inner shell whereby it will be purified.

3. In an apparatus of the character described a housing including an outer and an inner shell, said inner shell forming a water

chamber, said outer shell comprising a series of independent compartments, means whereby communication may be had between said compartments, an upstanding tube carried by said outer shell, means whereby communication may be had between said tube and the interior of said outer shell, one of said compartments being normally filled with water, means to maintain a circulation of air through the other compartments and said

tube and pass the air through the water in said inner shell and means to selectively dispense the air from said inner shell to said last mentioned compartment and said tube.

In testimony whereof I affix my signature 15 in presence of two witnesses.

ATHANASIOS PAPANASTASIOU.
